ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

GUIDE FOR THREAD-CUTTING TEMPLES.

1,141,654.

Specification of Letters Patent.

Patented June 1, 1915.

Application filed September 10, 1914. Serial No. 861,145.

To all whom it may concern:

Be it known that I, ALONZO E. RHOADES, a citizen of the United States, and resident of Hopedale, county of Worcester, State of Massachusetts, have invented an Improvement in Guides for Thread-Cutting Temples, of which the following description, in connection with the accompanying drawing, is a specification, like characters on the drawing representing like parts.

This invention relates to thread cutting temples for looms and has for its object to provide means to guide or direct the filling end into the field of action of the thread cutting device on the temple and also to hold the filling end in the field of action of the said device. Automatic looms employing thread cutting temples are also commonly provided with filling parting and holding devices which sever the filling of the filling carrier abandoned upon replenishment and then carry the parted end forwardly, bringing it into the field of action of the temple thread cutter so that it may be again severed close to the selvage. But the parted end is not infrequently jerked from or released by the device holding and carrying it forward so that as a result, the end is dropped, whipped or snapped out of the field of action of the temple thread cutter, so that severance adjacent the selvage is not effected.

The object of this invention is to present means for eliminating so far as possible this defect in operation and insuring the severing of the filling end adjacent the selvage.

The nature and object of the invention will appear more fully from the accompanying description and drawings and will be particularly pointed out in the claims.

The drawings show so much of an automatic filling replenishing loom as is necessary to an understanding of this invention.

In the drawings: Figure 1 is a top plan view of the right hand end of a portion of a Northrop automatic filling replenishing loom embodying a preferred form of the present invention, and Fig. 2 is a perspective view of a portion of the temple, temple thread cutter and guiding devices embodying this invention.

No detailed description of the general mechanism of the loom is necessary to an understanding of this invention.

The temple and thread cutter are for con-

venience, herein illustrated as of generally similar construction to that shown and described in the patent to W. F. Draper and E. S. Stimpson, No. 585,465 granted June 29, 1887. The stand 1 of the loom temple is secured in the usual manner to the breast beam of the loom. In this stand is mounted the slide bar 2 of the temple which carries at its rear end, the pod 3 and cap 4 between which is journaled the usual toothed roller. The thread cutting instrumentality is mounted and works in the rearward end of the strand 2 and comprises a cutting blade 5 and a coöperating hook shaped double blade 6 which has a forwardly and rearwardly reciprocating and also an oscillatory movement, all as described in the said patent to Draper and Stimpson so that when the filling end extending from the fell is brought between the blade 5 and the double blade 6 it will be severed.

As already explained, the filling end of the abandoned filling carrier is usually severed adjacent the filling carrier and then carried forwardly by suitable devices upon the abandonment of the filling carrier. Any suitable form of such filling, severing, and holding mechanism may be employed for this purpose but an appropriate form illustrated herein is the same as that disclosed in A. E. Rhoades' Patent No. 1,134,487, granted April 6, 1915. In the said Rhoades patent, upon the call for filling replenishment, a carrier 7 is automatically moved rearwardly toward the filling carrier or shuttle about to be boxed at the transfer end of the loom. This carrier is provided with a head 8 and on the head is an abraiding surface 9 which coöperating with the small abraiding surface upon the shuttle severs therebetween by abrasion the trailing filling. The severed end is at once caught upon the peripheral surface of the thread catching and holding member 10 also mounted on the head 8. This peripheral surface is of a thread adherent nature being described as composed of felt, cloth or similar material. The carrier 7 then moves forwardly and carries with it the parted end of the filling 11 which extends back to the fell of the goods being woven. As the end is thus carried back it is brought into position so that it will be severed by the temple thread cutting blades 5 and 6. But the filling end may not be severed at the first operation of the cutting blades 5 and 6; it may not be accurately

placed between the blades; it may be so loosely held or engaged by the holding device that it drops off while being carried forward and is then whipped or snapped or dropped out of the field of action of said cutters; or the filling end may break while being carried forward with the same result.

The filling end extends from the fell about in line with the opening between the pod 3 and the cap 4 of the temple and small grooves or notches 12 are sometimes provided to aid in locating the proper position of the filling end for severance by the temple thread cutter. But these are insufficient to guide or hold the filling end in position.

In the present invention two guides are preferably employed, one above and one below the path of the filling end. These guides may be formed in any suitable manner and secured by any suitable means to, or made a part of the temple stand. The form illustrated is a convenient form for securing the advantages of the invention and one which may be readily manufactured and attached to existing looms. The upper guide is shown as made of sheet metal, the effective portion of which is the laterally and forwardly extending guiding edge 13. The plate of which this is the edge may be constructed as shown in Fig. 2 and secured by set screws 14 to the stand of the temple. The lower guide is also shown as made of sheet metal, the effective portion of which is the guiding edge 15, also extending laterally and forwardly and also downwardly so as to cause it to diverge from the guiding edge 13. The metal plate 16 on which this edge is formed is preferably made in the form shown in Fig. 2 and secured to the bottom of the stand 2. This lower plate has a horizontal forwardly extending portion in which is formed the forwardly diverging notch 17. It is found in practice that these guiding edges serve to direct the filling end into the field of action of the cutting blades 5 and 6 and usually to cause the released or dropped end of the filling to fall into and be held by the notch 17 in the required position. If the filling end is whipped or snapped upwardly it contacts with the guiding edge 13 and is directed back into position so that it will fall into the notch 17. If it is simply dropped or released, instead of falling out of the field of action of the cutting blades it is guided in its fall by the edge 15 and brought back into the notch 17. The guiding edge 13 is just above the cutting plane and the guiding edge 15 extends laterally just below the cutting plane and then downwardly and forwardly. These guides therefore work together to insure the desired results and both of them are preferably employed, although

the upper guide may be omitted and desirable results secured, because the filling end 65 whether whipped or snapped or dropped is likely in the end to fall and will then be guided by the edge 15 into the required position.

Having fully described my invention, 70 what I claim as new, and desire to obtain by Letters Patent, is:

1. In a loom, a temple, a thread cutter carried thereby, means for carrying the filling end forwardly, a pair of vertically separated guides on said temple provided with laterally and forwardly extending guiding edges to guide the filling end into the field of action of said cutter, the lower of said guides having therein a forwardly opened 80 notch to receive and hold the filling end in position.

2. In a loom, a temple, a thread cutter carried thereby, means for carrying the filling end forwardly, a pair of vertically separated guides on said temple provided with laterally extending divergent guiding edges to guide the filling end into the field of action of said cutter, the lower of said guides having therein a forwardly opened notch to 90 receive and hold the filling end in position.

3. In a loom, a temple, a thread cutter carried thereby, means for carrying the filling end forwardly, a guide on said temple provided with a laterally, downwardly and 95 forwardly extending edge to guide a released filling end into the field of action of the said shuttle, said guide having a forwardly opened notch to receive and hold the filling end in position. 100

4. In a loom, a temple thread cutter, a guide having a laterally and forwardly extending edge just above the cutting plane of the cutter, a guide having a guiding edge extending laterally just below said plane 105 and then extending downwardly and forwardly, the two guiding edges acting to insure the guiding of a filling end into cutting position, the lower guide also presenting a forwardly opened notch to receive and hold the filling end in position. 110

5. In a loom, a temple thread cutter, a guide having a guiding edge extending laterally just below the cutting plane of the said cutter and then extending downwardly 115 and forwardly to direct a filling end into cutting position, said guide being also provided with a forwardly opened notch to receive and hold the filling end in position.

In testimony whereof, I have signed my name to this specification, in the presence of two subscribing witnesses.

ALONZO E. RHOADES.
